UNITED STATES PATENT OFFICE.

EDITH B. DOWN, OF WATERTOWN, NEW YORK.

ATTACHMENT FOR BEDS.

1,422,939.

Specification of Letters Patent.

Patented July 18, 1922.

Application filed February 11, 1922. Serial No. 535,910.

To all whom it may concern:

Be it known that I, EDITH B. DOWN, a subject of Great Britain, residing at Watertown, in the county of Jefferson and State 5 of New York, have invented certain new and useful Improvements in Attachments for Beds, of which the following is a specification.

This invention relates to attachments for 10 beds and more particularly to a patient elevating means.

An important object of this invention is to provide an auxiliary mattress for beds having novel means whereby one or both 15 ends of the same may be conveniently elevated by an attendant when it is desired to place a bed pan in position.

Further, the invention forming the subject matter of this application aims to provide 20 an auxiliary mattress for beds having depending side curtains which conceal the bed pan and give the patient a feeling of privacy when using the same.

Also, the invention aims to provide an 25 auxiliary mattress and operating means therefor which may be conveniently attached to hospital or other beds without altering the construction of the bed and without marring the appearance of the 30 same.

A further object is to provide an auxiliary mattress for beds which is sanitary, of highly simplified construction and cheap to manufacture.

35 Other objects and advantages of the invention will be apparent during the course of the following description.

In the accompanying drawing forming a 40 part of this application and in which like numerals are employed to designate like parts throughout the same,

Figure 1 is a perspective of the improved auxiliary mattress.

Figure 2 is a detail sectional view through 45 the elevating means for the auxiliary mattress.

Figure 3 is a detail horizontal sectional view through one of the brackets embodied in the invention.

50 Figure 4 is a perspective of one of the brackets.

Figure 5 is a side elevation of the improved auxiliary mattress applied.

Figure 6 is a fragmentary perspective of 55 the mattress.

Figure 7 is a detail sectional view through the mattress.

Figure 8 is a detail sectional view illustrating side curtains which may be used in connection with the auxiliary mattress.

In the drawing wherein for the purpose of illustration is shown a preferred embodiment of the invention the numeral 5 generally designates a bed which consists of a head 6, a foot 7, the usual side rails 8 and 65 the mattress 9.

The invention forming the subject matter of this application is in the nature of an auxiliary mattress or stretcher which consists of a rectangular frame 10 constructed 70 from tubular metal and of approximately the same length and width as the mattress. As illustrated in Figure 1, a stretcher body or mattress 12 is arranged within the frame and is provided with a series of gromets 14 75 which receive a lace 16 wound about the frame of the auxiliary mattress whereby to adjustably connect the auxiliary mattress to the frame. It will be seen that the auxiliary mattress is arranged above the main mattress and is provided with a centrally arranged opening 17 beneath which a bed pan may be arranged, in which case the bed pan rests upon the main mattress of the bed. Of course, the wall of the opening 17 may 80 be reinforced as indicated at 18. In carrying out the invention, the auxiliary mattress may be formed of a suitable flexible and washable material and may be of any desired thickness. Also a sheet may be extended over the auxiliary mattress and may 85 be secured to the frame by means of the lace 16.

The auxiliary mattress may be elevated at one or both ends by means of winch bars 22 95 having their end portions rotatably extended through transverse apertures in the upper portions of attaching brackets 23, the said attaching brackets being provided with locking pins 25 adapted to extend through transverse openings in the end portions of the winch bars whereby to detachably hold the winch bars in position. When it is desired to rotate the winch bars for either raising or lowering the auxiliary mattress the pins 25 100 may be removed and subsequently inserted for holding the mattress in position.

The auxiliary mattress is connected to the winch bars 22 by means of flexible elements 26 which as illustrated in Figure 1 are con- 110

nected to the frame adjacent the corners of the same and are connected to the end portions of the winch bars adjacent the brackets

23. It will be seen that when the winch bars 5 22 are turned in one direction the flexible elements 26 will be wound thereon for raising the auxiliary mattress, while when the winch bars are rotated in the other direction the auxiliary mattress will be lowered.
10. Each end portion of each winch bar is squared as indicated at 30 for engagement with a crank 31 forming a means whereby the several winch bars may be raised and lowered. The crank 31 will in practice be 15 so located that the same may be conveniently turned by the attendant.

The brackets 23 are provided with attaching portions 36 having longitudinally extending V-shaped grooves 37 which partially receive the posts of the bed, and the attaching portions 36 are firmly held in engagement with the posts of the bed by means of fastening bolts 39 extended through the attaching portions and through plates 40. By 20 tightening up on the nuts threaded on the bolts 39 the brackets may be securely connected to the bed.

In operation, the attendant may raise either one or both ends of the mattress when 30 it is desired to place a bed pan beneath the auxiliary mattress, or, when it is desired to elevate the patient for other reasons. It will be seen that with reference to Figure 5 35 that the upper portions of the brackets 23 are extended angularly so as to overhang the ends of the auxiliary mattress a direct

pull is obtained in operation. By reason of this arrangement longitudinal movement of the auxiliary mattress is prevented.

As illustrated in Figure 8, the improved 40 auxiliary mattress may be provided with side curtains or drops which protect the patient from drafts and which also gives a feeling of privacy.

The improved auxiliary mattress may also 45 be adjusted for supporting the patient in an inclined position, and further arrangements may be made for using the auxiliary mattress by adults or children.

I claim:—

In a bed the combination with brackets having V-shaped attaching portions adapted to engage the corner posts of a bed, of means to securely connect said V-shaped attaching portions to the corner of the bed, the upper 55 portions of said brackets being provided with transverse openings, winch bars rotatably extended through said openings, pins detachably locking said winch bars to said brackets the end portions of said winch bars 60 being squared, a crank adapted for connection with the squared end portions of said winch bars, an auxiliary mattress connected to said winch bars, the upper portions of said brackets being extended angularly to 65 overhang the ends of said mattress.

In testimony whereof, I have affixed my signature in the presence of two witnesses.

EDITH B. DOWN.
